VEHICLE SPRING MANUFACTURING
METHOD

Harry B. Clary, Oakland, Calif., assignor to Laher
Spring and Tire Corporation, Oakland, Calif.,
a corporation of Oregon

Application April 13, 1948, Serial No. 20,758

4 Claims. (Cl. 29—173)

1

This invention relates generally to methods for the manufacture of vehicle springs of the semi-elliptical leaf type.

The conventional method for the manufacture of vehicle springs of the elliptical leaf type is to separately handle and process each leaf of the spring assembly, throughout the successive heating, bending and hardening operations. For the bending operation each leaf must be bent by the use of special pattern strips or forms, and the forms for each leaf must be different. Leaves manufactured in this fashion must be carefully sorted and checked for each assembly, and frequently some cold bending is required for the final assembly. In making the final assembly it is difficult to maintain accurate alignment of the shackle bolt eyes which are customarily formed in the ends of the main leaf, thus further complicating the sorting and selection of the leaves for each final assembly. Such individual handling and processing operations materially add to the cost of the final spring, and require a relatively high degree of skill on the part of the workmen, both in the processing and final assembly operations.

It is a general object of the present invention to provide a method for the manufacture of vehicle springs which will avoid the individual handling and processing of the leaves as described above. The present method is characterized by the handling and processing of all of the leaves of a spring assembly as a unit, including the heating, bending and hardening operations, whereby in one general operation, which is no more difficult or time consuming than the processing of an individual leaf, all of the leaves of a complete spring assembly are completed.

Further objects of the invention include the elimination of separate forms or pattern strips for each leaf, facilitating proper alignment of the shackle bolt eyes in the final assembly, eliminating troublesome selection and sorting of individual leaves, facilitating making spot tests on production, and providing a spring manufacturing method which can be readily mastered by ordinary workmen without a long training period.

Additional objects of the invention will appear from the following description in which the preferred embodiment has been set forth in detail in conjunction with the accompanying drawing.

Referring to the drawing—

Figure 1 is a side elevational view showing an assembly of spring leaves prior to processing, and showing the majority of the secondary leaves

assembled upon that side of the main leaf, opposite from the side which the secondary leaves normally occupy in the completed spring.

Figure 2 is a plan view showing the assembly of Figure 1 in a bending machine for bending all of the leaves in one operation.

Figure 3 is an end view of the bending machine illustrated in Figure 2.

Figure 4 is a view like Figure 1, but showing the assembly after the bending operation.

Figure 5 is a view like Figure 1, but showing how the leaves after being processed in one assembly, are reassembled with the secondary leaves upon the convex side of the main leaf.

Figure 6 is a view like Figure 5, but showing all of the leaves held in close relationship by the center tie-bolt.

As previously stated it is conventional practice in the manufacture of vehicle springs of the semi-elliptical leaf type to separately process the different leaves, and then to assemble leaves of proper curvature to form the final spring. The present invention departs from such conventional practice in that after cutting the separate leaves from suitable steel stock, and forming eyes in the ends of the main leaf, the leaves are all loosely assembled with all or a majority of the secondary leaves disposed in the order of their length upon that side of the main leaf which subsequently becomes the convex side. While so assembled the leaves are heated and bent in one operation, after which they are hardened.

In Figure 1, I have shown the leaves of a spring loosely assembled in the manner described above. The main leaf 10 is formed with the end eyes 11, and all of the leaves are centrally drilled to receive the retaining bolt 12. The secondary leaves are numbered 13 to 18 inclusive. The leaves 14 to 18 inclusive are assembled in the order of their length upon the lower side of the main spring 10. Because the leaf 13 is too long to be accommodated between the eyes 11, it is placed upon the upper side of the main leaf 10. All of the secondary leaves are of slightly lesser thickness than the main leaf 10. For example the main leaf may be $\frac{1}{8}$ inch in thickness as compared to $\frac{1}{4}$ inch for the secondary leaves.

The entire assembly of Figure 1 is placed in a suitable heating furnace and heated to a proper temperature for hot bending. It is then placed in a suitable bending machine such as is illustrated in Figure 2, and which is adapted to bend all of the leaves in one bending operation. This machine consists of a work table 21 provided with parallel stationary and movable beams 22

and 23. The movable beam 23 is attached to a suitable operating device, such as the rod 24 of a pneumatic cylinder and piston device 26. The stationary beam 22 carries a plurality of threaded and adjustable thrust rods 31 to 42 inclusive, and the movable beam 23 carries similar rods 43 to 54 inclusive. The beam 23 also carries the thrust members 56 and 57, which have substantially the same spacing as the rods 36 and 37. The spring assembly designated generally by number 58 is adapted to rest upon a suitable surface such as provided by the side-by-side beams 59.

With suitable adjustment of the various thrust rods, it is evident that when the beam 23 is retracted the spring assembly can be deposited upon the I beams 59, and thereafter beam 23 can be advanced to bend the entire assembly to the desired shape, as illustrated in Figure 2. In conjunction with this bending operation it is desirable to provide a set of inner and outer pattern strips or forms 61 and 62. These pattern strips have a general curvature corresponding to that to which the complete assembly is bent, and they are provided with central openings 63 and 64 adequate to pass the ends of the retaining bolt 12. One set of forms serves for the entire assembly, thus obviating forms for all of the individual leaves as required in the past.

When the beam 23 is retracted following a hot bending operation all of the leaves straighten out a certain amount, but the main leaf 10 springs back a greater amount than the secondary leaves, due to the fact that it is made of thicker stock. In a typical instance the leaves immediately after the bending operation will appear as shown in Figure 4. The main leaf 10 has the least curvature or "arch" of all of the leaves. The secondary leaf 13 has considerably more arch than the main leaf 10, but slightly less than the leaf 14. Leaf 15 has slightly more arch than the leaf 14 and leaf 16 slightly more arch than leaf 15. The leaves 16, 17 and 18 have substantially the same arch.

It may be explained at this point that in many instances all of the secondary leaves can be assembled on one side of the main leaf for the bending and subsequent processing operations. Where it is necessary, because of its length, to place the leaf 13 on the upper side of the assembly (Figure 1), then it is generally necessary to bend the assembly to a slightly greater arch than would otherwise be the case.

The assembly is now subjected to suitable treatment for hardening the leaves, and which can be carried out by conventional methods involving for example the reheating of the assembly followed by its immersion in oil or like liquid to chill the same.

After the hardening operation, the retaining bolt 12 is removed, and the various leaves reassembled in the order illustrated in Figure 5. Assuming that leaf 13 has been bent on the outside, then the arch of the main leaf 10 is checked before final assembly, and any arch in excess of the proper amount is removed by cold bending. In the assembly of Figure 5 it will be noted that the leaf 13 has an arch considerably greater than the main leaf 10, and the arch for each of the leaves 14, 15 and 16 is progressively greater. The springs can now be clamped together by tightening the tie-bolt 91, to form the final assembly of Figure 6. All of the leaves are now in surface contact. The ends of leaf 13 press upon the end portions of the main leaf 10, leaf 14 presses at its ends upon leaf 13, the ends of leaf 15 press

upon leaf 14, and the ends of leaf 16 press upon leaf 15. This is what is termed in the trade as "proper snap" for the secondary leaves. Leaves 16, 17 and 18 may be substantially unstressed in the final assembly, or in other words, they are not provided with any snap.

It will be evident from the foregoing that I have provided a method for the manufacture of leaf springs which greatly reduces the number of handling operations required. It is only necessary to handle a complete assembly of all of the leaves, as distinguished from the prior practice of handling the leaves separately. In fact the expense and time required to heat, bend and harden all of the leaves in one general operation is no greater than that required in the past for each individual leaf. Only one set of forms or pattern strips is required for all of the leaves, whereas in the past a set of forms must be provided for each individual leaf, thus involving considerable expense for these parts as well as consuming time for their insertion in the bending machine. Also the final assembly is simpler than conventional practice, because leaves which have been prepared in this fashion can be more readily assembled into the final spring. Troublesome selection and sorting of the leaves used for the final assemblies is eliminated and because all of the leaves are bent in one operation, no difficulty is experienced in maintaining proper alignment of the shackle bolt eyes.

By virtue of the simplicity and savings effected by my method, the over-all cost of producing springs in considerable quantities is greatly reduced, and the capacity of a given plant installation can be greatly increased. Spot tests on production can be readily made at frequent intervals as distinguished from the difficulty in making checks on production by the prior described method. The various manual operations involved are quite simple and can be readily mastered by ordinary workmen without a long period of training.

I claim:

- 45 1. In a method for the manufacture of vehicle springs of the semi-elliptical leaf type, assembling the unhardened leaves generally in the order of their length, the secondary leaves being disposed on that side of the main leaf which is to be the concave side after bending, applying a retaining member through the centers of the leaves to loosely retain the assembled relationship, heating the complete assembly, bending the complete assembly to thereby provide the proper curvature in one operation for all of the leaves, reheating and chilling the assembly to harden the same, and then reassembling the leaves in normal order with the secondary leaves on the convex side of the main leaf.
- 50 2. In a method for the manufacture of vehicle springs of the semi-elliptical leaf type, the steps of assembling the unhardened leaves in the general order of their length on that side of the main leaf which is to be the concave side after manufacture, and with the centers of the leaves aligned on a common axis, heating the assembly, bending the assembly while hot to provide in one bending operation the proper curvature for all of the leaves and with the secondary leaves being bent to curvatures greater than that of the main leaf, hardening the bent leaves, and assembling the leaves with the secondary leaves on the convex side of the main leaf.
- 55 3. In a method for the manufacture of vehicle springs of the semi-elliptical leaf type, the steps

of loosely assembling the unhardened leaves in the general order of their length on that side of the main leaf which is to be the concave side after manufacture and with the centers of the leaves aligned on a common axis, heating the assembly, bending the assembly while hot to provide in one bending operation the proper curvatures for all of the leaves and with the secondary leaves being bent to final curvatures greater than that of the main leaf, hardening the bent leaves while so assembled, and then reassembling the leaves with the secondary leaves on the convex side of the main leaf.

4. In a method for the manufacture of vehicle springs of the semi-elliptical leaf type, the steps of assembling the unhardened leaves in the general order of their length on that side of the main leaf which is to be the concave side after manufacture, and with the centers of the leaves aligned

on a common axis, applying retaining means to the leaves to loosely retain the assembled relationship, heating the assembly, bending the assembly while hot to provide in one bending operation the proper final curvature for all of the leaves, and with the secondary leaves being bent to curvatures greater than that of the main leaf, hardening the bent leaves while so assembled, and then reassembling the leaves with the secondary leaves on the convex side of the main leaf.
